(57) **CLAIM**

The ornamental design for a push button for switches, as shown and described.

DESCRIPTION

1. Push button for switches

1.1 : Front

1.2 : Right

1.3 : Top

1.4 : Bottom

1.5 : Top side perspective view

1.6 : Bottom side perspective view

1.7 : A-A cross sectional view

In each figure, the parts indicated by the solid lines, excluding the dotted lines, are the parts for which a design is to be registered as a partial design; the back view is omitted because it is identical to the front view; the left side view is omitted because it is identical to the right side view; the "A-A cross-sectional view" is a cross-sectional view of the article when it is cut by the A-A line of the bottom view. The broken lines showing portions of the push button for switches are for illustrative purposes and form no part of the claimed design.

1 Claim, 7 Drawing Sheets
